US00D996388S

(12) **United States Design Patent** (10) **Patent No.:** **US D996,388 S**
(45) **Date of Patent:** **** Aug. 22, 2023**

(54) **HANDHELD COMMUNICATION DEVICE**

(71) Applicant: **MOTOROLA SOLUTIONS, INC.**,
Chicago, IL (US)

(72) Inventors: **Goktug Duman**, Oakland Park, FL
(US); **Lanting L Garra**, Sunrise, FL
(US)

(73) Assignee: **MOTOROLA SOLUTIONS, INC.**,
Chicago, IL (US)

(**) Term: **15 Years**

(21) Appl. No.: **29/737,460**

(22) Filed: **Jun. 9, 2020**

(51) LOC (14) Cl. **14-03**
(52) U.S. Cl.
USPC **D14/138 G**; D14/137

(57) **CLAIM**

The ornamental design for a handheld communication device, as shown and described.

DESCRIPTION

FIG. 1 is a front perspective view of the first embodiment of a handheld communication device, showing our new design; FIG. 2 is a rear perspective view thereof; FIG. 3 is a front view thereof; FIG. 4 is a rear view thereof; FIG. 5 is a first side view thereof; FIG. 6 is a second side view thereof; FIG. 7 is a top view thereof; FIG. 8 is a bottom view thereof.

FIG. 9 is a front perspective view of the second embodiment of the handheld communication device; FIG. 10 is a rear perspective view thereof; FIG. 11 is a front view thereof; FIG. 12 is a rear view thereof; FIG. 13 is a first side view thereof; FIG. 14 is a second side view thereof; FIG. 15 is a top view thereof; and, FIG. 16 is a bottom view thereof.

The broken lines shown in the drawings illustrate portions of the handheld communication device that form no part of the claimed design.
